DESIGN FOR A TEXTILE FABRIC

Neuman B. Starr, New York, N. Y.

Application March 4, 1939, Serial No. 83,338

Term of patent 3½ years

To all whom it may concern:

Be it known that I, Neuman B. Starr, a citizen of the United States of America, residing at New York city, in the county of New York and State of New York, have invented a new, original, and ornamental Design for a Textile Fabric, of which the following is a specification, reference being had to the accompanying drawing, forming part thereof.

In the drawing the single figure is a face view of a Textile Fabric, showing my new design.

I claim:

The ornamental design for a textile fabric, substantially as shown.

NEUMAN B. STARR.
